Primary Examiner — Michelle E. Wilson*Assistant Examiner* — Tracey J Bell(74) Attorney, Agent, or Firm — Fitch, Even, Tabin & Flannery LLP(57) CLAIM

I claim the ornamental design for an earring, as shown and described.

DESCRIPTION

FIG. 1 is a perspective view of an earring, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines illustrate portions of the earring and form no part of the claimed design.
